UNITED STATES PATENT OFFICE.

HEINRICH JACOB, OF FRIEDENAU, NEAR BERLIN, GERMANY, ASSIGNOR TO THE FIRM OF OPTISCHE ANSTALT C. P. GOERZ AKTIENGESELLSCHAFT, OF FRIEDENAU, NEAR BERLIN, GERMANY.

BINOCULAR.

Application filed February 4, 1922. Serial No. 534,052.

To all whom it may concern:

Be it known that I, HEINRICH JACOB, a citizen of the German Republic, and resident of Friedenau, near Berlin, Germany, have invented certain new and useful Improvements in and Relating to Binoculars, of which the following is a specification.

This invention relates to binoculars provided with two ocular tubes arranged at a distance from each other and consists in a binocular construction which is of high mechanical stability even if its casing is manufactured from thin sheet of light metal such as aluminium and in a process for manufacturing such strong instrument casing in a cheap manner.

The new binocular construction and the several steps of manufacturing its casing in accordance with the invention are, illustrated on the accompanying drawing and will hereafter be described with reference to the drawing.

Figure 1 is a part central axial section and a part side elevation.

Figure 2 is a section on the line 2—2 of Figure 1 looking in the direction of the arrows.

Figures 3-8 illustrate several succeeding steps in the manufacture of the instrument casing.

Figures 9 and 10 are a plan and a central axial section of a decorating cover for a part of the casing.

Figure 11 is a side elevation of the casing provided with the decorating cover of Figures 9 and 10, the decorating cover partially being shown in section.

The instrument shown in Figures 1 and 2 is a so-called Galilean binocular of that kind wherein the setting of the instrument is effected by shifting the object-glasses within the instrument casing. In the construction in accordance with the invention the instrument casing consists of a main box-like part wherein the object-glasses are slidably mounted and of separate eye-piece tubes which are inserted in said box-like casing element and are fastened thereto.

The object-glasses are mounted on a common support 1. The figures of the drawing

show only one object-glass 2. The support 1 and the object-glasses are mounted in a box-like casing 3 having a cylindrical side wall which, in the construction illustrated, is closed at the end directed towards the object to be viewed at by a cover 4 which is of a shape suited to the shape of the casing 3 and encircles the front end of same and closes and at the same time stiffens the latter. The casing 3 has a spectacles-like cross section; the two circular cylindrical sections at the ends of the casing forming receptacles for the slideable object glasses and being connected together by an open space in which the support 1 of the object-glasses is 65 adjustably mounted. At the eye-piece end, the casing 3 has two beaded rings 5 which stiffen the said casing and into which are inserted ocular or eye-piece tubes 6 which are made separately from the casing 3. The 70 closing of the instrument casing at the end directed towards the object to be viewed at is effected by covering glasses 7, which, according to the drawing, are constituted by flat discs, but which could also be spherocentric or of lens shape. 8 is an eye-piece lens which is connected to the corresponding tube 6 in any desired known manner. 9 is a screw for moving the object-glass support 1; the said screw carries outside the 75 casing a setting button 10 and is mounted in the central hollow space of the box casing 3 in a fixed manner. The ocular sided cover of the box casing is provided with a projecting button forming a bearing for screw 9.

The box casing 3 is made symmetrical as owing to the elimination of the movable unsymmetrical shape disappears. According to the drawing, the cover 4 for the whole opening of the object-glass casing is formed in one piece and provided with an upturned edge fitting the outlines of the casing and fulfills at the same time the closing of the casing and the separate object of stiffening 95 it.

The construction of the instrument casing is made with a view of a special method of manufacturing it. It is so designed that the manufacture can be made with but little 100

hand work and mainly by modern methods of metal drawing and pressing. To this end the casing is manufactured in several separate parts each of which being adapted to simple manufacture by machinery. The principal part is the box-like casing for the object-glasses; two further parts are the ocular tubes which are fitted in openings in the cover of said box-like casing. A further part of the casing which preferably is provided is a cover for the end opening of said box casing. All of these parts are adapted to be manufactured from sheet metal by drawing and pressing operations, it being specially important that the firm connection between the box-like casing and the ocular tubes likewise can be and is effected by a drawing operation namely the tightening of the cylindrical wall of the box-like casing.

As to the manufacture of the box-like casing for the object glasses it is effected by suitably shaping a sheet metal blank of spectacles-like shape, preferably provided with a centre hole as illustrated in Figure 3. This plate of sheet metal is at first subjected to the action of pressing and drawing tools so as to form therein the contour of the cover of the box-like casing as illustrated in Figures 4 and 5 of the drawing. Thereafter by successive drawing operations the free edge of the sheet-metal plate is formed into a cylindrical wall of spectacles-like cross section, so as to bring the sheet blank of Figure 3 into the casing form of Figure 6. Then the cover of such casing is provided with two lateral holes each concentric to one of the circular cylindrical sections at each end of the casing, giving the casing the form illustrated in Figure 7. Then conical ocular tubes 6 are inserted into said holes of the casing, the tubes being so dimensioned that the edge of the wide end of each tube abuts against the edge of the hole in the casing cover. This being done the cylindrical wall of the box-like casing is tightened by suitable drawing operations. The effect thereof is the formation of the beaded rings 5 encircling the lower edges of the ocular tubes and bringing same likewise into the form of beaded rings in tight embracement with said beaded rings 5 of the casing. Thus the conical ocular tubes 6 are firmly connected with the box-like casing. At the same time the casing is highly stiffened. The manner of connection between the casing and the ocular tubes can be clearly seen from Figures 1 and 8 of the drawing. In a preferred embodiment the tightening of the cylindrical wall of the casing is extended through the whole circumference of the casing so that a continuous beaded ring around the ocular sided edge of the casing is formed as appearing in Figure 8 of the drawing. This giving a valuable stiffening

of the bridge-like portion of the casing between the lateral circular cylindrical parts.

Within the casing manufactured as above described the optical elements of the binocular are mounted. This being done the open end of the box-like casing is closed by a suitably shaped cover allowing the entrance of light in the direction towards the object-glasses.

According to Figures 1 and 2 a cover 4 is used which is likewise made of sheet metal by pressing operations and which has an upturned edge encircling the free edge of the cylindrical wall of the box-like casing. The cover 4 has a high stiffening effect similarly to the beaded ring 5 at the upper edge of the casing. As appearing from Figure 1 the cover 4 may be used for pressing the mountings of plates 7 against the lower edge of the box-like casing.

It is to be noted that the previously described method of manufacturing the binocular casing secures high strength and rigidity even if the casing is manufactured of light metal such as aluminium because the several elements are hardened by the drawing process and the whole casing stiffened by the beaded ring 5 and the cover 4 as above stated.

However, light metal such as aluminium can not be provided in a reliable manner with a firmly adhering coating of precious metal such as gold, so that there exists some difficulty to make instruments with casing light in weight in accordance with this invention which are decorated with precious metal coatings. In accordance with a further part of this invention this difficulty can be overcome by providing a separate decorating part of thin sheet metal of spectacles-like shape and exactly the same configuration as the upper cover of the box-like casing and by fastening it on said cover by bending its edge about the beaded ring 5. Such spectacles-like shaped decorating part is illustrated in Figures 9 and 10 of the drawing whereas Figure 11 shows it after mounting on the casing illustrated in Figure 8. Such decorating part may either consist of heavy sheet metal such as brass and suitably decorated, for instance by an electrolytic deposit of gold etc. or of a thin sheet of precious metal.

The front cover 4 of the casing may be decorated in the same way as the rear cover of the casing.

A special advantage of the new manner of manufacturing the binocular casing consists therein that the number of parts required is reduced to about one half of the number of parts hitherto required in the manufacture of Galilean binoculars.

What I claim is:

1. In a binocular with axially shiftable object-glasses a box-like casing, two object-

- glasses axially shiftably mounted therein in guiding contact with the wall of said casing and fastened to a non-rotatable carrier likewise mounted within said casing, means to shift said carrier with said object-glasses within said casing, and two ocular tubes separately and firmly mounted within said object-glass casing at a distance from each other.
- 10 2. In a binocular a box-like casing, a pair of object glasses mounted on a common carrier axially shiftable within said casing from end to end and two ocular tubes separately and firmly mounted within said object glass casing at a distance from each other in alignment with said object glasses.
- 15 3. In a binocular a box-like casing, a pair of object glasses mounted on a common carrier axially shiftable within said casing from end to end and two ocular tubes separately and firmly mounted within said object-glass casing at a distance from each other, the edge of the cover of the box-like casing containing for each ocular tube a beaded ring portion 20 encircling the lower edge of the ocular tube and securing it in position within said casing.
- 25 4. In a binocular a box-like casing, two object glasses, a carrier for same, said carrier with the object glasses shiftable from end to end of said casing without rotation therein, and two ocular tubes separately mounted within said object-glass casing at a distance from each other, the edge of the 30 cover of the box-like casing containing the ocular tubes being formed in a beaded ring continuously surrounding the whole casing and projecting above the lateral wall of the casing, portions of said projecting beaded ring of the casing encircling the lower edges of the ocular tubes and securing them in position within said casing.
- 35 5. In a binocular a drawn thin-walled sheet metal casing of spectacles-like cross section and substantially cylindrical side wall, a central adjusting screw rotatably mounted within said casing and provided with an operating handle or knob outside the casing, a carrier shiftably but non rotatably 40 mounted on said adjusting screw within said casing and having fastened thereto the object-glasses slidable within substantially circular lateral cylindrical portions of the casing, the cover of the drawn sheet metal casing provided with lateral openings in alignment with the object-glasses, drawn sheet metal conical ocular tubes inserted in said lateral openings of the cover of the object-glass casing, a beaded ring projecting over the lateral wall of said casing forming the edge of the casing and encircling the adjacent edge of an ocular tube so as to firmly secure it in position, and a sheet metal cover having an upturned edge for the object-sided end of said object-glass casing 45 the upturned edge of the cover tightly embracing the lower edge of the side wall of the casing, the cover hermetically sealing the inner cavity of the casing, but allowing the entrance of light at places in front of the object-glasses.
- 50 6. In a binocular a drawn thin-walled sheet metal casing of spectacles-like cross section and substantially cylindrical side wall, a central adjusting screw rotatably mounted within said casing, a member comprising the object-glasses mounted on said screw and axially shiftable within said casing, a central projection on the cover of the drawn sheet metal casing forming a bearing for said adjusting screw and carrying on its top side a screw actuating knob fixed on said screw, the casing cover being provided laterally to said projection and screw actuating knob with openings in alignment with the object-glasses, drawn sheet metal conical ocular tubes inserted in said lateral openings of the cover of the object-glass casing, a beaded ring projecting over the lateral wall of said casing forming the edge of the casing and encircling the adjacent edge of an ocular tube so as to firmly secure it in position, and a sheet metal cover having an upturned edge for the object-sided end of said object-glass casing, the upturned edge of the cover tightly embracing the lower edge of the side wall of the casing, the cover hermetically sealing the inner cavity of the casing, but allowing the entrance of light at 55 places in front of the object-glasses.
- 60 7. In a binocular provided with object and ocular glasses in axial alignment with each other in combination a box-like casing of light metal having a substantially cylindrical side wall and closed at one end with 65 hermetically sealing it, said cover allowing
- 80 8. In a binocular a drawn thin-walled sheet metal casing of spectacles-like cross section and substantially cylindrical side wall, a central adjusting screw rotatably mounted within said casing and provided with an operating handle or knob outside the casing, a carrier shiftably but non rotatably mounted on said adjusting screw with 70 in said casing and having fastened thereto the object-glasses slidable within substantially circular lateral cylindrical portions of the casing, the cover of the drawn sheet metal casing provided with lateral openings in alignment with the object-glasses, drawn sheet metal conical ocular tubes inserted in said lateral openings of the cover of the object-glass casing, a beaded ring projecting over the lateral wall of said casing forming the edge of the casing and encircling the adjacent edge of an ocular tube so as to firmly secure it in position, and a sheet metal cover having an upturned edge for the object-sided end of said object-glass casing 75 the upturned edge of the cover tightly embracing the lower edge of the side wall of the casing, the cover hermetically sealing the inner cavity of the casing, but allowing the entrance of light at places in front of the object-glasses.
- 85 9. In a binocular a drawn thin-walled sheet metal casing of spectacles-like cross section and substantially cylindrical side wall, a central adjusting screw rotatably mounted within said casing, a member comprising the object-glasses mounted on said screw and axially shiftable within said casing, a central projection on the cover of the drawn sheet metal casing forming a bearing for said adjusting screw and carrying on its top side a screw actuating knob fixed on said screw, the casing cover being provided laterally to said projection and screw actuating knob with openings in alignment with the object-glasses, drawn sheet metal conical ocular tubes inserted in said lateral openings of the cover of the object-glass casing, a beaded ring projecting over the lateral wall of said casing forming the edge of the casing and encircling the adjacent edge of an ocular tube so as to firmly secure it in position, and a sheet metal cover having an upturned edge for the object-sided end of said object-glass casing, the upturned edge of the cover tightly embracing the lower edge of the side wall of the casing, the cover hermetically sealing the inner cavity of the casing, but allowing the entrance of light at 90 places in front of the object-glasses.
- 100 10. In a binocular a drawn thin-walled sheet metal casing of spectacles-like cross section and substantially cylindrical side wall, a central adjusting screw rotatably mounted within said casing, a member comprising the object-glasses mounted on said screw and axially shiftable within said casing, a central projection on the cover of the drawn sheet metal casing forming a bearing for said adjusting screw and carrying on its top side a screw actuating knob fixed on said screw, the casing cover being provided laterally to said projection and screw actuating knob with openings in alignment with the object-glasses, drawn sheet metal conical ocular tubes inserted in said lateral openings of the cover of the object-glass casing, a beaded ring projecting over the lateral wall of said casing forming the edge of the casing and encircling the adjacent edge of an ocular tube so as to firmly secure it in position, and a sheet metal cover having an upturned edge for the object-sided end of said object-glass casing, the upturned edge of the cover tightly embracing the lower edge of the side wall of the casing, the cover hermetically sealing the inner cavity of the casing, but allowing the entrance of light at 105 places in front of the object-glasses.
- 110 11. In a binocular a drawn thin-walled sheet metal casing of spectacles-like cross section and substantially cylindrical side wall, a central adjusting screw rotatably mounted within said casing, a member comprising the object-glasses mounted on said screw and axially shiftable within said casing, a central projection on the cover of the drawn sheet metal casing forming a bearing for said adjusting screw and carrying on its top side a screw actuating knob fixed on said screw, the casing cover being provided laterally to said projection and screw actuating knob with openings in alignment with the object-glasses, drawn sheet metal conical ocular tubes inserted in said lateral openings of the cover of the object-glass casing, a beaded ring projecting over the lateral wall of said casing forming the edge of the casing and encircling the adjacent edge of an ocular tube so as to firmly secure it in position, and a sheet metal cover having an upturned edge for the object-sided end of said object-glass casing, the upturned edge of the cover tightly embracing the lower edge of the side wall of the casing, the cover hermetically sealing the inner cavity of the casing, but allowing the entrance of light at 115 places in front of the object-glasses.
- 120 12. In a binocular a drawn thin-walled sheet metal casing of spectacles-like cross section and substantially cylindrical side wall, a central adjusting screw rotatably mounted within said casing, a member comprising the object-glasses mounted on said screw and axially shiftable within said casing, a central projection on the cover of the drawn sheet metal casing forming a bearing for said adjusting screw and carrying on its top side a screw actuating knob fixed on said screw, the casing cover being provided laterally to said projection and screw actuating knob with openings in alignment with the object-glasses, drawn sheet metal conical ocular tubes inserted in said lateral openings of the cover of the object-glass casing, a beaded ring projecting over the lateral wall of said casing forming the edge of the casing and encircling the adjacent edge of an ocular tube so as to firmly secure it in position, and a sheet metal cover having an upturned edge for the object-sided end of said object-glass casing, the upturned edge of the cover tightly embracing the lower edge of the side wall of the casing, the cover hermetically sealing the inner cavity of the casing, but allowing the entrance of light at 125 places in front of the object-glasses.
- 130 13. In a binocular provided with object and ocular glasses in axial alignment with each other in combination a box-like casing of light metal having a substantially cylindrical side wall and closed at one end with

- a cover in one piece with the side wall the cover provided with two substantially circular openings at a distance from each other a sheet metal decorated part made of heavy metal superposed on said cover, two ocular tubes firmly mounted in said lateral openings of the cover of the casing and of the decorated part and an object glass carrier mounted within the cavity of said casing allowing shifting of the object glass from 10 end to end of said casing.
- 5 In testimony whereof I have signed this specification.

HEINRICH JACOB.
